5 Claims. (Cl. 29—157)

The present application is a continuation-in-part of my copending application Serial No. 308,960, filed September 16, 1963, and entitled "Pump and Tank Coupling Means."

The invention herein disclosed relates to an improved method for coupling a motorized pump unit in communication with the discharge fitting of a liquid containing vessel, such as a laundry tub, tank or tray or other liquid receiver or container to be periodically pumped dry, with the pump unit suspended from above by such fitting.

Laundry tubs in present day use are commonly provided with an outlet fitting or drain opening through the bottom thereof at a relatively slight elevation above a basement or similar floor on which the tub rests; and the method contemplates a direct suspended connection of a motorized pump unit to such fitting. However, a considerable inconvenience has arisen in the past in effecting a leak-proof union of the pump unit to the tub discharge, primarily because of the vertically restricted and dark space beneath the latter. This requires the plumber or other installer to stoop in a very awkward position beneath the tub and, supporting the motorized pump unit manually, turn the latter about an upright axis to thread its central, upper intake eye onto the threaded tub discharge fitting. The bulk and weight of the pump unit makes this a difficult and cumbersome operation, which is further complicated as to awkwardness by the presence of pre-assembled discharge fitting means and piping of the pump, electrical pump motor cable, and the like, all of which have the effect of adding to the difficulty of making a proper water-tight joint at the tub.

It is therefore a general object of the invention to provide an improved method involving the use of multiple-part coupling means to facilitate the water-tight, vertically suspended union of a motorized pump unit to the externally threaded discharge fitting of a laundry tub or other bottom-drainable, liquid containing vessel. Pursuant to the subject method, the assembling operation requires only the proper manual suspension of the pump unit beneath the discharge fitting (assisted, possibly, by some sort of temporary physical floor support for the motorized pump unit), and the threading of a simple jam nut onto the tube fitting to complete the assembly, without requiring any turning or twisting of the assembled pump unit itself, and thus avoiding the drawbacks of inconvenience and awkwardness referred to above.

Certain very practical considerations have led to the development of the method. While pump drained laundry tubs have to some extent supplanted gravity drained tubs, as in suburban residences having overhead plumbing, and hence required by state and local codes to dispose of the laundry water immediately because of a possible health hazard, it has been found impossible to sustain the pump unit directly from the tub outlet and still obtain a satisfactory liquid-tight seal at the joint, particularly in view of the imposed weight of the pump and motor structure.

That is, regardless of whether the tub as supplied by its manufacturer was ultimately gravity-drained or pump-drained, an entirely conventional sort of pump coupling was applied to an entirely conventional tub fitting; and this resulted, in a pump-drained installation, in a great difficulty in obtaining a good seal, since the tub fitting

2

was never designed in the first place for mechanical evacuation. Moreover, a coupling applied to the tub fitting and capable of being gasketed could not support significant weight.

5 The method of the invention overcomes these drawbacks, making it possible for the plumber to effect a perfect seal at the conventional tub outlet, while the latter supports a substantial pump and motor weight, and the installation is made quickly and easily, with the 10 pump's discharge always located in proper position when the connection is tightened.

The coupling method makes this possible because of its use of a sealing gasket at the weight supporting connection; whereas tubs have heretofore been pump-drained only by resort to the use of slip fittings incapable of supporting substantial weight, and never, to my knowledge, by employing a gasketed joint which will both seal and support motor and pump weight.

Moreover, the improved method makes it possible for 20 standard pipe coupling or nipple members to be employed in combination with a standard annular flanged jam nut to effect the desired sealed connection and suspension of the pump unit to and from the tank or tub. These standard parts are converted to the purposes of 25 the invention in a manner to be described.

Yet another specific object is to provide a method of 30 coupling pump intakes of different diameters to a standard tub discharge fitting; and of coupling a pump unit to the discharge means of either a single tub or a dual discharge tub unit, with the ease and convenience mentioned above.

The foregoing as well as other objects will become 35 more apparent as this description proceeds, especially when considered in connection with the accompanying drawings illustrating the invention, wherein:

FIG. 1 is a fragmentary perspective view showing a sealed suspended connection of a motorized pump unit to a bottom-drainable liquid vessel, typically shown as a laundry tub, as effected by the method of the invention;

FIG. 2 is a fragmentary view in vertical section of the tub and pump as thus coupled;

FIG. 3 is a fragmentary sectional view showing a modification of the method in the coupling to a standard tub outlet fitting of a motorized pump unit having perhaps a smaller or larger diameter intake than the pump unit; and

FIG. 4 is a fragmentary view in section similar to FIGS. 2 and 3 illustrating the method as performed in 50 mounting the pump to a dual discharge type of pump unit, calling for the use of a supplemental branched fitting.

The method of the present invention involves the use 55 of a coupling which is generally designated by the reference numeral 10; and it is employed in the manner indicated above to suspend an electrically motorized pump unit 11 from the tub 12, in vertically spaced relation to a basement or like floor 13 on which the tub 12 is supported by an appropriate frame structure 14. The unit 60 11 includes a motor 16, the motor being electrically energized through a conductor cable 17, equipped with a switch 17', and a pump housing 18, whose impeller (not shown) is directly connected to the motor. The pump housing includes a central upper, tubular intake part or member 19 at the pump intake eye, and a radial or tangential, tubular discharge fitting 20, which is connected by an L 21 and other conventional check valve provisions 22 to an upwardly extending discharge pipe 23.

70 The pump housing 18 is also provided with an upwardly extending pressure transmitting control tube 24

opening downwardly into housing 18 at a predetermined radial point thereon; and the function of this tube in the start-stop control of pump unit 11, in response to varying liquid level in tub 12, is explained in detail in my Letters Patent No. 3,043,225 of July 10, 1962. It is seen by reference to FIG. 1, that the assembly of pump unit 11 including motor and pump housing 18, discharge fitting 20 and associated means, wiring cable 17, and the like presents a quite bulky and cumbersome object, very awkward of manipulation in threading the same upwardly onto the tub discharge fitting from a restricted space and inconvenient, dark location, in the manner heretofore necessary. Accordingly, the improved method utilizes coupling 10 to eliminate these drawbacks, while still providing a weight bearing suspension of the motorized pump unit 11 from the tub or tank 12 thereabove.

As illustrated in FIG. 2, the tub 12 conventionally comprises a horizontal bottom panel 25 provided with a circular opening 26 which receives a discharge mouth or fitting 27 for the downward drainage of the tub. Fitting 27 is provided with drain openings 28 at its bottom, a cylindrical upwardly extending wall 29 which has a standard external thread at 30, and an outwardly flared, annular top flange 31 abutting the margin of the tub opening 26 from above. An annular cupped clamp ring 32 similarly engages the tub bottom 25 from beneath, the clamp ring encircling fitting wall 29 and being clamped against the tub by a nut 33 applied to the external fitting thread 30. The invention does not concern this mount of the fitting 27 to tub 12, which may be considered a typically simple one. In other types of tub, such as cement tubs, this fitting is cast into the raw cement and is not removable or turnable; and it is to be understood that the method of the invention is also suited for coupling pump units on them. In other words, the method makes possible the mounting of the pump on the tub without need to move any tub part.

The coupling 10 essentially comprises three components which, though of basically standard production nature, are nevertheless specially related to one another and to the tub discharge fitting 27 and pump intake eye part 19, as regards dimensional characteristics, in a manner hereinafter described. These components are a cylindrical adapter sleeve 35, resembling a standard pipe nipple threaded at one end, in that it is provided at its lower end with standard pipe size external threading 36 having liquid-tight sealing engagement with standard internal threads 37 of the intake eye part 19 of pump unit 11. As will appear, the threads 37 are incapable of mating with the threading of the tub discharge fitting or member 27. At its upper end, the nipple-like adapter 35 is upset radially to provide an annular suspending lip or flange 39 of greater diameter than the body of the adapter.

The second component of the coupling 10 is an annular sealing gasket or washer 41 of a suitable deterioration-resistant, compressible material, such as a synthetic plastic. This gasket has a relatively thin annular, axially extending flange 42 of a size to fit readily within the top of sleeve adapter 35, and a relatively thickened annular shoulder or flange 43 which extends radially over the sleeve adapter flange 39, being coextensive with the latter in external diameter.

The third component of coupling 10 is an annular jam nut 45, which is provided with a standard internal thread at 46 to mate with the external thread 30 of tub fitting 27; and beneath this threaded zone, the jam nut 45 provides an annular, radially extending suspending flange 47. The flange 47 is of lesser inner diameter than the O.D. of sleeve adapter flange 39, but slightly greater than the O.D. of the sleeve body to permit a sliding fit of nut 45 along the latter.

In using the coupling 10, its adapter member 35 is tightly threaded into the standard internal thread 37 of pump intake part 19, this in effect constituting the coupling, a unitary extension of pump unit 11 sealed at the

intake eye of its pump housing 18. A lubricating type of sealing is usually employed at this threaded joint, but no other special seal is required.

Then, holding the pump and coupling assembly fixedly and coaxially beneath the tub discharge mouth fitting 27 (or suitably supporting the same on an appropriate floor support), the plumber or installer simply slips jam nut 45 upwardly and threads the latter onto the threading 30 of fitting 27, rotating only the nut 45, in this operation. As tightly taken up, and with the pump discharge 20 and associated parts oriented angularly in a horizontal plane as desired, the nut 45 compresses gasket 41 against fitting 27 to effect a liquid tight seal of coupling 10 and unit 11 to the latter. Also, by engagement of the nut flange 47 beneath the sleeve flange 39, the coupling affords a weight-suspension support for the motorized pump unit 11. This manipulation may be performed in a fraction of the time, difficulty and inconvenience involved in the threading rotation of the entire pump unit directly onto the tub fitting 27.

Furthermore, in order to provide an effective connection to the tub outlet, pursuant to the previous procedure above mentioned, the problem was presented of making a water-tight seal of the pump intake upwardly against only the thread of the tub fitting; and it is difficult to effect the proper seal against the thread and still have the pump discharge fitting (such as the fitting 20 with associated connections 21, 22, 23) oriented in the proper angular direction. If the pump intake is backed off some amount for this purpose, the effectiveness of the seal is necessarily diminished or destroyed. All of this is compounded by the physical difficulty of making the connection, as described above. It has also heretofore been impossible to introduce special sealing gasket means in threaded connections of this sort due to the absence of any shoulder means at the joint against which to compress the gasket.

However, the present invention permits the use of the compressible annular gasket 41 for the desiredly tight seal, with the pump unit properly oriented as desired, for example, as shown in FIG. 1, before the final compression of the gasket is effected on tightening jam nut 45.

Heretofore, pump-drained tubs have been employed, primarily in suburban installations having so-called overhead plumbing, because of the requirement of state and local codes that laundry water be disposed of immediately, rather than being accumulated in a sump or the like, in view of the possible arising of a health hazard. Objections of the sort mentioned above remain, however, in regard to the impossibility of getting a good liquid seal at a tub fitting which was never intended to have a seal at a thread, and the great difficulty of tightening the thread connection and still have the pump discharge properly located. It is for such installations that the present invention contributes ease and speed of assembly of the pump unit to the tub, in a manner to conveniently and in a minimum of space suspend the pump from the tub, while getting a perfect seal with the pump discharge properly located.

Reference has been made above to the fact that the coupling employs standard fitting and nut parts capable of ready modification for the purpose of the invention. While these parts may vary in dimension as produced by different manufacturers, a typical coupling 10 according to the invention will include an adapter sleeve 35 made of a standard 1 1/4 inch pipe nipple of selected length having threading 36 at its lower end matching the internal thread 37 at pump intake 19. The outer diameter "A" (FIG. 2) of such a nipple is a standard 1.660 inch.

The jam nut 45 is preferably a 1 1/2 inch slip nut of a plain, unthreaded slip fitting or tail piece, just as available commercially as the nipple for adapter sleeve 35. Typically, such 1 1/2 inch slip nut has a minor diameter "B," or thread crest diameter at its internal threads 46, of 1.762 inch to mate with the threading of discharge member 27, which will accommodate the 1.660 O.D. "A" of

sleeve nipple member 35, and its threads 36. However, the minimum O.D. of the available 1½ inch slip nut beneath its threading 46 is typically a true 1½ inch, which will not receive the nipple component.

Accordingly, the invention contemplates the opening up of the slip nut at its minimum throat diameter to a diameter "C" of, say, 1.665 inch at the jam nut flange 47, thus to accommodate the sleeve nipple. As indicated above, the upper end of the nipple is radially outwardly upset to provide the annular top flange 39, in a diameter "D" of, say, 1.755 inch.

Thus, the sleeve flange 39 will radially inwardly overlap the nut flange 47 to the extent of about 0.090 inch along a diameter, for the desired weight-suspending support of the pump unit 16 through the agency of coupling 10, as the latter is applied to tub discharge fitting 27. Such a suspension support of a pump unit from a tub is impossible by resort to known and commercially available slip fitting tail pieces, which are unthreaded and hence incapable of suspending weight.

Mention has been made above of the use of a standard pipe nipple having a standard 1.660 inch thread 36 at its lower end to thread into the intake part 19 of pump housing 18, such arrangement permitting the use of a standard (though modified) slip member for the jam nut 45, and thus adapting the pump for a perfectly sealed, weight supporting mount to the standard tub discharge fitting 27. However, some manufacturers supply a motorized pump having a smaller sized intake eye, for instance one inch, so that ordinarily the adapter means used for a larger diameter intake, including the modified nipple element, cannot be used. In order to make the adaptation to the smaller diameter pump intake, the invention contemplates the use of the coupling of FIG. 3, generally designated 49.

Coupling 49 includes adapter sleeve means, generally designated 50, which is of two-part construction. One of these parts is an upper tubular or annular member 51 adapted to telescope within the opening of the flange 47 of the jam nut 45, the latter being of an internal diameter at the flange 47, as before, to telescopingly receive member 51; and as in the first embodiment adapter member 51 is radially outwardly flanged at 52 for supporting coaction with flange 47. A simple compressible washer or gasket 53 is interposed between flange 52 and the bottom of tub fitting 27.

The second part of the tubular coupling means 50 of coupling 49 is a standard nipple 54 threaded at both ends; and the upper adapter member 51 is internally threaded at 55 to sealingly receive nipple 54. The diameter at the threaded joint 55 is standard for the member 54, which is chosen in a diameter such that its lower threading at 56 will mate with the internal threading of the pump intake part 19. This has been instanced above as, say, one inch, or less than the O.D. of a one-piece adapter sleeve 35, such as is employed in the embodiment of FIG. 2. By the same token, a so-called reducing bushing can be employed in the adapter 10 to fit the same to a pump intake of greater diameter than that accommodated by the normal adapter sleeve 35. Accordingly, it is seen that in one adaptation or another, the improved method has versatility in the coupling to tubs of pump intakes of substantially different diameters.

As clearly appears in FIG. 4, the method of the invention is readily practiced in the suspended connection of a pump unit to a dual discharge type of tub or container unit 58, i.e., having like discharge fittings 59, 60 for subdivided portions of its interior. For such a dual unit, a branched type of connector 61 is employed, in the form of a casting having laterally spaced bosses 62, each internally threaded at 63 for mating engagement with the external threading of the discharge fittings 59, 60. Adapter casting 61 provides a connecting manifold 64 for these

discharge members leading to a single, downwardly opening and externally threaded discharge mouth 65.

The branched manifold fitting 61, as a casting, differs substantially from the usual, relatively thin walled discharge fitting 27 of a laundry tub, which may have the external threading 30 simply rolled thereon. However, as in the earlier embodiment, with fitting 61 tightly applied to the discharge members of the divided tub 58, the same procedure is followed in suspending the pump unit 11 from the tub. Reference numerals corresponding to those employed in FIG. 2 are used to designate corresponding parts of the coupling means 10, the jam nut 45 having mating threading engagement from beneath with the single discharge member 65 with the branched manifold member 61.

What I claim as my invention is:

1. A method of suspending a motor driven pump at the internal threading of its intake from a rigid tub or like container discharge fitting which is externally threaded but incapable of threadedly mating with the pump intake threading, comprising providing a tubular adapter externally threaded at one end thereof for mating threaded engagement with said pump intake threading and having a radially outwardly projecting flange of predetermined outer diameter, providing a jam nut internally threaded for mating engagement with the threading of said container discharge fitting and having an internal flange of smaller inner diameter than the outer diameter of said adapter flange, telescoping said jam nut on said adapter with the nut rotatable about said adapter and the nut flange positioned for supporting engagement from beneath with the adapter flange, then threading said adapter into fixed threaded engagement with the pump intake, manually supporting said pump and adapter thereon above the floor beneath the tub and under said discharge fitting in a predetermined angular relationship to the latter, and then rotating said nut into threaded engagement with the container discharge fitting, while thus supporting and without rotating said pump and adapter from said predetermined angular position, to bring said adapter, as sustained by said nut and sustaining said pump, into fixed and sealed communication with said container fitting.

2. The method of claim 1, in which the ratio of the outer diameter of said adapter to the crest diameter of the internal threading with which said jam nut is provided corresponds substantially to the ratio of the outer diameter of a standard 1½" pipe nipple to the crest diameter of internal threading of a standard 1½" slip nut.

3. The method of claim 1, in which the ratio of the outer diameter of said adapter to the crest diameter of the internal threading with which said jam nut is provided is approximately 1.660/1.762.

4. The method of claim 1, in which said container has a single discharge fitting threadedly engaged from beneath by said jam nut.

5. The method of claim 1, in which the container has dual discharge means, said jam nut being upwardly threaded onto a single discharge fitting of said dual means.
